HOLLOW FORMER FOR THE MANUFACTURE
OF SHOES

Pierre Henri Gallan, Marseille, France

Application August 13, 1951, Serial No. 241,621
In France February 10, 1951

4 Claims. (Cl. 12—133)

1

The object of this invention is to provide an improved hollow last for all shoe-sizes permitting the complete and rapid manufacture of shoes by sewing.

According to the present invention, the hollow shoe last comprises a hollow metal shell including a toe, arch, and heel portion of a shape corresponding to that of the shoe to be formed, said shell having in its upper surface a parallel-sided longitudinal opening extending from a point near the tip of the toe portion to a point near the rear end of the heel portion, an upper shaping block corresponding to the shape of the upper vamp portion of the shoe mounted above the hollow metal shell and engaged at its forward lower part in the opening of the shell, a bracket secured to the upper shaping block and extending along the top of the shell to the tip of the heel portion thereof, a releasable latch mounted on the bracket and adapted to engage with the heel portion of the shell to secure the bracket and the upper shaping block to the shell, and a handle mounted on the bracket for the manipulation of the last.

One side portion of the upper shaping block 25 may be arranged to overlap the upper surface of the shell.

The bracket is preferably a two-armed angle bracket one of the arms of which is secured to the upper shaping block and the other of which is arranged rearwardly along the top of the shell to the tip of the heel portion thereof, and carries the latch and the manipulation handle.

The longitudinal opening at the upper surface of the shell may have a centering recess into which the forward part of the upper shaping block engages.

In the annexed drawings, given by way of non-limiting example of one of the forms of construction of the invention:

Fig. 1 shows the assembled last in side elevation.

Fig. 2 is a corresponding plan view.

The metallic shell 1 is hollowed at its lower part 2 to form an arch portion and has a parallel-sided longitudinal opening in its top surface 3. 4 45 is a toe portion and 5 is a heel portion having an inwardly directed flange 6.

The longitudinal opening has a centering recess 8 and receives a wooden upper shaping block 7 with a projecting part 9 overlapping the metallic part. To the block 7 is secured one arm of a two-armed bracket 10, the other arm carrying a pivoted latch 11 for engagement under the flange 6. 12 is an upstanding rod for manipulation of the last.

2

The assembly of the two parts 1 and 7 constitutes the complete last.

However, to prevent the first sole from falling into the open underpart of the shell when placed thereagainst, there is secured to the underside of the upper shaping block 7 a filler block (shown in broken line) the lower surface of which, in the assembled position, is level with the lower periphery of the shell and thereby supports the first sole in position. Additionally, in practice, the first sole would slightly over-lap the lower periphery of the shell for further support at the edges.

The upper of the shoe is mounted on the block 7 while the shell 1 supports the hard tip, the stiffening, and the wing portions.

In assembling the shoe, the first sole is put in position, the periphery of the upper is turned down and the outer sole then covers the assembly, which is then glued.

When the assembly is finished, the block 7 with the filler block attached thereto is drawn back by disengaging the latch 11 from the flange 6.

The first sole, the upper and the outer sole are then sewn, leaving at the interior of the shoe the metallic shell which maintains in shape, during this operation, the hard tip, the stiffening, and the wing portions, avoiding any deformation thereof.

I claim:

1. A hollow shoe last comprising a hollow metal shell including a toe, arch and heel portion of a shape corresponding to that of the shoe to be formed, said shell having in its upper surface a parallel-sided longitudinal opening extending from a point near the tip of the toe portion to a point near the rear end of the heel portion, an upper shaping block mounted above the hollow metal shell and engaged at its forward lower part in the opening of the shell, a bracket secured to the upper shaping block and extending along the top of the shell to the tip of the heel portion thereof, a releasable latch mounted on the bracket and adapted to engage with the heel portion of the shell to secure the bracket and upper shaping block to the shell, and a handle mounted on the bracket for manipulation of the last.

2. A hollow shoe last comprising a hollow metal shell including a toe, arch and heel portion of a shape corresponding to that of the shoe to be formed, said shell having in its upper surface a parallel-sided longitudinal opening extending from a point near the tip of the toe portion to a point near the rear end of the heel portion, an

upper shaping block mounted above the hollow metal shell and engaged at its forward lower part in the opening of the shell, one side portion of the upper shaping block being arranged to overlap the surface of the shell, a two-armed angle bracket secured by one of its arms to the upper shaping block and having its other arm arranged rearwardly along the top of the shell to the tip of the heel portion thereof, a releasable latch mounted on the said other arm and adapted to engage with the heel portion of the shell to secure the bracket and the upper shaping block to the shell, and a handle mounted on the bracket for manipulation of the last.

3. A hollow shoe last comprising a hollow metal shell including a toe, arch and heel portion of a shape corresponding to that of the shoe to be formed, said shell having in its upper surface a parallel-sided longitudinal opening extending from a point near the tip of the toe portion to a point near the rear end of the heel portion and a centering recess at the front of said opening, an upper shaping block corresponding to the shape of the upper vamp of the shoe mounted above the hollow metal shell and engaged at its forward lower part in the opening of the shell and in the centering recess thereof, a two-armed angle bracket secured by one of its arms to the upper shaping block and having its other arm arranged rearwardly along the top of the shell to the tip of the heel portion thereof, a releasable latch mounted on the said other arm and adapted to engage with the heel portion of the shell to secure the bracket and the upper shaping block to the shell, and a handle mounted on the bracket for manipulation of the last.

4. A hollow shoe last comprising a hollow metal

shell including a toe, arch and heel portion of a shape corresponding to that of the shoe to be formed, said shell having in its upper surface a parallel-sided longitudinal opening extending from a point near the tip of the toe portion to a point near the rear end of the heel portion and a centering recess at the front end of said opening, a solid upper shaping block corresponding to the shape of the upper vamp of the shoe mounted above the hollow metal shell and engaged at its forward lower part in the opening of the shell and in the centering recess thereof, a two-armed angle bracket secured by one of its arms to the upper shaping block and having its other arm arranged rearwardly along the top of the shell to the tip of the heel portion thereof, an inwardly extending flange at the upper part of the heel portion of the shell, a pivoted latch member mounted on the said other arm of the bracket for engagement under said flange to secure the bracket and upper shaping block to the shell, and an upstanding rod secured to said other arm of the bracket to serve as a manipulating handle for the last.

PIERRE HENRI GALLAN.
